The ornamental design for knit boot, as shown and described.

DESCRIPTION

FIG. 1 is a side perspective view of a knit boot showing my new design;

FIG. 2 is a side elevational view thereof;

FIG. 3 is an opposite side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The cross-hatched shading in FIGS. 1-7 represents a soft knit or crocheted material that forms the knit boot. The broken lines that define the bounds of the claimed design form no part thereof
